US0D1083081S

(12) **United States Design Patent** (10) **Patent No.:** **US D1,083,081 S**
(45) **Date of Patent:** **** Jul. 8, 2025**

(54) **INHALER**

(71) Applicant: **NiPPharma Co., Ltd.**, Tokyo (JP)

(72) Inventor: **Shinichi Ono**, Tokyo (JP)

(73) Assignee: **NiPPharma Co., Ltd.**, Tokyo (JP)

(**) Term: **15 Years**

(21) Appl. No.: **29/923,409**

(22) Filed: **Dec. 29, 2023**

(30) **Foreign Application Priority Data**

Jul. 7, 2023 (JP) ..... 2023014134 D

(51) **LOC (15) Cl.** **29-02**

(52) **U.S. Cl.**

USPC **D24/110**

(57) **CLAIM**

The ornamental design for an inhaler, as shown and described.

DESCRIPTION

FIG. 1 is a perspective view of the inhaler of my new design, with the lid closed;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a perspective view of the inhaler of my design, with the lid opened;

FIG. 9 is a front elevation view thereof;

FIG. 10 is a back elevation view thereof;

FIG. 11 is a left elevation view thereof;

FIG. 12 is a right elevation view thereof;

FIG. 13 is a top plan view thereof; and,

FIG. 14 is a bottom plan view thereof.

1 Claim, 14 Drawing Sheets
